(57) **CLAIM**

The ornamental design for an oxygen mask, as shown and described.

DESCRIPTION

FIG. 1 is a front, perspective view of an oxygen mask according to an embodiment.

FIG. 2 is a right side view of the oxygen mask shown in FIG. 1.

FIG. 3 is a left side view of the oxygen mask shown in FIG. 1.

FIG. 4 is a top view of the oxygen mask shown in FIG. 1.

FIG. 5 is a bottom view of the oxygen mask shown in FIG. 1.

FIG. 6 is a front view of the oxygen mask shown in FIG. 1.

FIG. 7 is a rear view of the oxygen mask shown in FIG. 1; and,

FIG. 8 is a rear, perspective view of the oxygen mask shown in FIG. 1.

In the drawings, the broken lines are for the purpose of illustrating portions of the oxygen mask that form no part of the claimed design.

1 Claim, 8 Drawing Sheets
